HAIR DRYER

Horst Genger, Chicago, Ill., assignor to Brettford Manufacturing, Inc., Schiller Park, Ill., a corporation of Illinois

Filed May 26, 1964, Ser. No. 80,154

Term of patent 14 years

(Cl. D86—10)

The dominant features of the design are shown in full lines in the drawing.

I claim:

The ornamental design for a hair dryer, as shown and described.
